(57) **CLAIM**

The ornamental design for an electrical device box with extensions, as shown and described.

DESCRIPTION

FIG. 1 is a front view of electrical device box with extensions; FIG. 2 is a left side view thereof;

FIG. 3 is a rear view thereof;

FIG. 4 is a right side view thereof;

FIG. 5 is a bottom view thereof;

FIG. 6 is a top view thereof;

FIG. 7 is a rear perspective view thereof; and,

FIG. 8 is a front perspective view of electrical device box with extensions.

The broken lines are included for the purpose of illustrating environmental features and form no part of the claimed design.
